CHAIR FRAME

John Kolbe, Warsaw, Ind., assignor to Arnolt Corporation, Warsaw, Ind., a corporation of Indiana

Application July 8, 1957, Serial No. 46,856

Term of patent 14 years

(Cl. D15—1)

I claim:

The ornamental design for a chair frame, as shown.
